UNITED STATES PATENT OFFICE.

MARTIN V. HAMMACK, OF PROVIDENCE, RHODE ISLAND.

DESIGN FOR A BADGE-PIN.

SPECIFICATION forming part of Design No. 28,014, dated September 15, 1896.

Application filed July 31, 1896. Serial No. 801,254. Term of patent 3½ years.

To all whom it may concern:

Be it known that I, MARTIN V. HAMMACK, a citizen of the United States, residing at Providence, in the State of Rhode Island, 5 have invented and produced a new and original Design for Badge-Pins, of which the following is a specification, reference being made to the accompanying drawings, showing a part thereof.

10 Figure 1 represents the top view of a badge-pin, showing my design. Fig. 2 is a side view of the same, and Fig. 3 represents a section taken in the line 3 3 of Fig. 1.

15 The leading features of my design consist in the representation of a bird with spread

wings having in its bill a bug or beetle and having panels with portraits therein upon the wings.

In the drawings, A represents the body of the bird, B the head, and C the bill, in which 20 is held the bug or beetle D, and the spread wings E E are provided with the panels F F, inclosing the portraits G G.

What I claim is—

25 The design for a badge-pin herein shown and described.

MARTIN V. HAMMACK.
